JEWELRY COMPONENT OR SIMILAR ARTICLE

Karl C. Augenstein, Cranston, R. I., assignor to
Speidel Corporation, a corporation of Rhode
Island

Application June 8, 1950, Serial No. 10,412

Term of patent 14 years

(Cl. D45—1)

To all whom it may concern:

Be it known that I, Karl C. Augenstein, a citizen of the United States of America, residing at Cranston, county of Providence, and State of Rhode Island, have invented a new, original, and ornamental Design for a Jewelry Component or Similar Article, of which the following is a specification, reference being had to the accompanying drawing, forming a part thereof.

Fig. 1 is a top plan view of a jewelry component or similar article, showing my new design;

Fig. 2 is a side elevational view of the jewelry component shown in Fig. 1;

Fig. 3 is an end elevational view looking from bottom to top at the jewelry component shown in Fig. 1; and

Fig. 4 is an end elevational view of the jewelry

component looking from top to bottom at the jewelry component shown in Fig. 1.

I claim:

The ornamental design for a jewelry component or similar article, substantially as shown.

KARL C. AUGENSTEIN.
